METHOD OF MAKING INFLATABLE BALLS

Mason Scudder, Clayton, Mo., assignor to
Rawlings Manufacturing Company, St. Louis,
Mo., a corporation of Missouri

Original application February 12, 1938, Serial No.
190,177. Divided and this application April 15,
1939, Serial No. 268,012

1 Claim. (Cl. 154—16)

This invention relates to a method of making inflatable balls of the kind in which the cover or outer casing of the ball is made up of pieces of leather or other suitable material arranged with their marginal edges in abutting relationship, and secured by an adhesive to the exterior of an inflated member of spherical shape or form. This application is a division of my application Ser. No. 190,177, filed February 12, 1938.

One serious objection to prior inflatable balls of the general kind referred to, is that they cannot be grasped and held securely by the fingers of the user, and hence, cannot be thrown, spun or manipulated as easily or accurately as footballs, basketballs and similar balls of the kind that are equipped with a cover or outer casing made up of sections of leather joined together by sewed seams. This, of course, is due to the fact that the outer casing is perfectly smooth and devoid of depressions, ridges, or any other means that tends to prevent the user's fingers from slipping on the casing when the ball is being caught or carried, or which aids the user's fingers to get a purchase or grip on the casing when the ball is being thrown or manipulated in the game in which it is employed.

The object of my present invention is to provide a novel method for manufacturing a ball that is as easy to grasp, hold and manipulate as an inflatable ball of the kind that is equipped with a sewed or stitched cover or outer casing.

Figure 1 of the drawings is a perspective view, partly broken away, illustrating one form of ball that can be produced by the method which constitutes my present invention.

Figure 2 is a fragmentary sectional view of said ball, taken on the line 2—2 of Figure 1.

Figure 2^a is a detail view, showing how the sections or pieces of material that constitute the outer casing are skived preparatory to the operation of securing said sections in position.

Figure 3 is a view similar to Figure 2, illustrating another form of ball capable of being produced by my method, wherein the depression in the outer surface of the cover of the ball is produced by skiving or deforming the edge portion of one section and leaving the opposed edge of the adjacent section square or unskived.

Figure 4 is a view similar to Figure 2, illustrating another form of ball capable of being produced by my method, wherein the depression in the outer surface of the casing is produced by channeling, instead of skiving, the undersides of adjacent sections of the casing and then pressing said channeled portions inwardly.

Figure 4^a is a detail view of one of the casing sections, showing the channel in the underside of same.

Figure 5 is a view similar to Figure 2, illustrating still another form of ball capable of being produced by my method, wherein the depression in the outer surface of the casing is produced by forming grooves on the underside of the sections of the casing at points some distance inwardly from the edges of said sections, and then pressing said grooved portions inwardly to form the depression previously referred to; and

Figure 5^a is a detail view, showing the groove that is formed in the underside of one of the casing sections before said section is applied.

I have herein illustrated and described my method as being used to produce a football, basketball, or the like, that comprises an inflatable bladder A, a flexible shell B that surrounds said bladder, and an outer casing or cover C made up of pieces of leather or other suitable sheet material that is cemented onto the shell B, or secured to the outer surface of said shell by a suitable adhesive, the bladder A being preferably provided with an air valve or equivalent device D accessible from the exterior of the casing for inflating said bladder. The shell B may be of any preferred construction, but generally, it is constructed in the form of an envelope of canvas, felt or some other suitable non-stretchable fabric to which a coating of rubber or rubber compound is applied and molded so as to produce a seamless outer shell that has a smooth surface.

The outer casing C, as previously stated, is made up of a plurality of pieces or sections of leather that are permanently attached to the shell B by cement or the like. The shape and number of said sections are immaterial, but said sections are preferably made of the same general shape or outline as the sections employed to produce sewed or stitched outer casings for footballs, basketballs and the like. In the ball herein illustrated, the outer casing or cover of the ball

comprises two main parts that have the shape or outline of the figure 8, and each of said main parts comprises or is made up of either two long sections, or four short sections y, as is common practice in the construction of sewed leather casings for inflatable balls. The ball above described differs from prior balls of the type that comprise a "cemented on" outer casing, in that the outer casing or cover of the ball, instead of having a perfectly smooth exterior, is provided with an outer surface in which a depression x

55

of irregular shape or outline is formed so as to produce a finger-gripping surface which is practically the same as that of a ball casing made up of sections of leather joined together by inturned seams. The particular shape, form or outline of said depression x is immaterial, but I prefer to make it in the outline of the figure 8, so that the ball will present substantially the same appearance as a conventional football or basketball provided with a sewed or stitched outer casing.

The method that I have devised for producing the ball above described contemplates reducing the thickness of certain portions of the casing sections, preparatory to applying said sections, and then pressing said portions of reduced thickness inwardly during or subsequent to the operation of securing said sections in position, thereby producing a casing whose outer surface is broken up by a depression, groove or valley that assists the user's fingers to firmly grasp and hold the ball when it is in use. The reduction in thickness of certain portions of the casing sections may be effected by compressing or condensing said portions, or by removing material from said sections by a skiving operation, channeling operation or grooving operation. Preferably, material is removed from the casing sections at the edges of same, but if desired, the material can be removed from the sections at points some distance inwardly from the edges of same. One convenient way to produce the depression x is to taper the adjacent edges of some of the sections of the casing C, as shown in Figure 2, so that after said sections have been cemented in operative position on the shell B of the ball, there will be a slight valley or depression x at the point where the opposed edges of adjacent sections meet. The tapering of the sections can be effected by compressing or deforming the edge portions of said sections or by removing or cutting away material at the edges of said sections. In the ball shown in Figures 1 and 2, the edge portions of some of the sections that constitute the cover of the ball have their undersides skived at 1, as shown in Figure 2a, preparatory to applying said sections to the shell B, and during or subsequent to the operation of cementing said sections to the shell B the skived portions of said sections are pressed inwardly or downwardly toward the center of the ball, with the result that a valley or depression x is formed in the outer surface of the casing. In the ball shown in Figure 1, the valley or depression x has the form or outline of the figure 8, and consequently, it closely simulates the appearance of a conventional foot ball or basket ball provided with a sewed outer casing.

Instead of deforming or skiving both opposed edges of two adjacent sections, one section may be provided with a square edge 2, as shown in Figure 3, and the adjacent section may be provided with a skived edge like that shown in Figure 2a, with the result that when the sections are applied to the shell B and secured thereto, the inwardly pressed portion or portions of the skived section or sections will constitute a de-

pression x on the outer surface of the ball casing.

Figures 4 and 4a illustrate how the depression x may be formed by channeling the underside 5 of the edges of adjacent sections at 3, as shown in Figure 4a, and then pressing said channeled portions inwardly against the shell B, as shown in Figure 4.

While I prefer to skive, channel or otherwise 10 taper or deform the opposed edges of adjacent sections to produce a depression x located at the point where some of the sections of the casing meet, said depression may be located at a point some distance inwardly or away from the meeting 15 edges of the sections of the casing. In Figures 5 and 5a I have shown how much a depression x' may be produced by forming a groove 4 on the underside of the casing sections, preparatory to applying them to the shell B, and thereafter 20 forcing said grooved portions inwardly toward the shell, thus producing a casing made up of sections having square edges butted tightly together and disposed in flush relationship, and provided in its outer surface with a groove x' of any preferred configuration or shape, that assists 25 the user's fingers to grip or hold the ball when it is in use.

The ball previously described presents substantially 30 the same appearance and can be grasped and manipulated the same way as a ball provided with a sewed or stitched outer casing, due, of course, to the fact that the depression in the outer surface of the casing imparts to the ball the same finger-gripping characteristic that 35 is inherent in a foot ball, basket ball or the like, whose outer cover is made up of sections of leather joined together by inturned seams, and my improved method permits such a ball to be manufactured easily and at a low cost.

While I have herein described my method as 40 being used to produce an inflatable ball of the kind in which a flexible shell encases an inflatable bladder, and in turn, is encased in an outer cover made up of pieces of material that are cemented to the outer surface of said shell, I wish 45 it to be understood that my method is applicable to the manufacture of any type or kind of play ball equipped with an outer cover made up of pieces of material arranged with their marginal 50 edges in abutting relation and secured by an adhesive to the exterior of an inflated spherical member.

Having thus described my invention, what I 55 claim as new and desire to secure by Letters Patent is:

A method of making an inflatable ball, characterized by forming cover sections having tapered marginal edge portions, arranging said cover sections on an inflated spherical member 60 with their edges in abutting relationship, and securing said sections by an adhesive to said member, and pressing the tapered edge portions of said cover sections inwardly, thereby producing a ball whose cover is provided with a valley or depression of irregular shape or outline.

MASON SCUDDER.
